UNITED STATES PATENT OFFICE.

OTTO THOMASCHEWSKI, OF NEWARK, NEW JERSEY.

CUTLERY CLEANER.

Application filed August 31, 1925. Serial No. 53,477.

The main object of this invention is to provide a device for grinding, sharpening, and cleaning cutlery. The device essentially consists of a plurality of rouge disks and a 5 grinding wheel which are mounted on a shaft and are rotated either manually or thru another source of power, and when brought into contact with an article of cutlery such as a knife or fork, are adapted to 10 clean and polish the same.

The above and other objects will become apparent in the description below, in which characters of reference refer to like-named parts in the drawing.

15 Referring briefly to the drawing, Figure 1 is a front elevational view of the cleaner and polishing machine.

Figure 2 is a top plan view of the same.

20 Figure 3 is an end elevational view of Figure 1.

Figure 4 is a longitudinal partially sectioned elevational view of a portion of the shaft, showing the means provided for shifting the position of one of the rouge wheels 25 to compensate for various thicknesses of knife blades.

Referring in detail to the drawing, the numeral 10 indicates the base upon which the entire device is mounted. At both the ends 30 of the base, a pair of standards 11 and 12 rise upwardly and have annular horizontal openings at their upper ends in which are journaled the ends of a spindle 13 which has a crank handle 14 fixed to one end thereof. These shafts are retained in place by caps 15. A flat surface is provided on the top of these caps for the purpose of forming a seat for the ends 16 of semi-oval straps 17 and 18 which form yokes above 40 and below the spindle 13. The lower strap 18 is not connected to the flat surfaces of the caps 15 but is connected instead to the sides of the standards 11 and 12. Mounted intermediate the length of the spindle are 45 a pair of rouge disks 19 and 20. The rouge disk 19 is rigidly mounted in place on the spindle. The disk 20 is adapted to slide longitudinally on the spindle 13 by mounting the layers of fabric 21, of which the 50 rouge disk is composed, on a collar 22 which is flanged at both ends and at one of the flanged ends is provided with a key 23 rigid with the collar which is adapted to be guided and slid in a longitudinal channel 24 extending lengthwise on the spindle 13. This 55 key forms part of the substantial flange 25

integral with one end of the sleeve 22 and is adapted for the purpose of permitting the rouge disk 20 to be moved longitudinally of the spindle 13 and at the same time rotate 60 with the latter. Positioned at a point distant from the collar flange 25, an additional flange 26 is rigidly mounted on the spindle for the purpose of retaining the coiled spring 27 in place on the spindle between 65 said flange 26 and the collar flange 25, which is provided for the purpose of urging the rouge disk 20 toward the fixed rouge disk 19 so that the adjacent faces of both disks may contact with each other. The mutually 70 adjacent surfaces of the disks 19 and 20 have convex surfaces so that a knife or the like may be readily inserted between both disks when it is desired to clean and polish the same. On the straps 17 and 18 above 75 and below the disks where their convex surfaces contact, are spaced-apart lugs 27* between which a knife is adapted to be guided in a vertical plane when cleaning said knife between the rouge disks 19 and 20. Near 80 one end of the spindle adjacent the rouge disk 19 are a plurality of relatively small oval-edged rouge rollers 28 which are mounted on the spindle, one alongside the other, and are separated by a small gap 29 in 85 which a fork or other cutlery utensil which may not be cleaned and polished between the rouge disks 19 and 20, is inserted. At the end of the spindle opposite to the crank handle 14 is a carborundum wheel 30 rigidly 90 mounted on said spindle and is used for the purpose of providing knives or other cutting utensils with cutting edges in the well known manner. Mounted on the bottom side of the strap 18 is a housing 31 in which 95 a drawer 32 is slidable, said drawer being used for the purpose of storing the rouge compound with which the surfaces of the disks 19 and 20 and rollers 28 are treated.

In using this device for cleaning cutlery 100 such as a knife, fork, or the like, the spindle 13 is rotated. If the article to be cleaned is a knife, the same is placed upon the vertical edges of the straps 17 and 18 and guided in a vertical plane between the rouge rollers 105 19 and 20. The spindle in being rotated causes the convex surfaces of the mutually adjacent sides of the rouge rollers to clean and polish the article. When forks are to be cleaned, the same are inserted in the gaps 110 29 between the rollers 28 and the spindle is likewise rotated. Spoons and the like are

cleaned by placing the same in contact with the peripheries of these rollers which are semi-oval in outline. To permit the shifting of one of the disks 20 to compensate for different thicknesses of knife blades, said disk is made so that it may be slid longitudinally of the spindle 13. This is accomplished by providing the collar 22 with a key which registers in a slot in the spindle, thus locking the collar rigidly to the spindle and at the same time permitting longitudinal movement of the disk 20, it being normally urged in contact with the disk 19 by the spring 27.

15 I claim:

In a cutlery cleaner, a rotating spindle, a flange on one side of the center of said spindle, a disk fixed to said spindle having a convex surface, a movable disk mounted 20 slidably adjacent the fixed disk, said movable disk having a complementary convex surface, the convex surfaces of the fixed and movable disks forming a substantially tri-

angular channel between said disks, a sleeve forming part of the movable disk and slidably mounted on said spindle, said spindle having a slot extending diametrically thru the spindle, a key rigid with the sleeve registering in the slot in said spindle, a spring surrounding said spindle between the flange and the sleeve of the movable disk urging said movable disk against said fixed disk, spaced-apart standards supporting said spindle at its ends, a pair of oppositely curved straps having their ends attached to said standards, and spaced-apart lugs projecting from said straps intermediate their length, said lugs being positioned above and below the fixed and movable disks, the channel between said lugs being aligned with the triangular space between said fixed and movable disks, said lugs forming a guide for cutlery.

In testimony whereof I affix my signature.

OTTO THOMASCHEWSKI.
